UNITED STATES PATENT OFFICE.

ABRAHAM N. WOLF, ALLENTOWN, PENNSYLVANIA.

MIDDINGS-SEPARATOR.

SPECIFICATION forming part of Letters Patent No. 230,597, dated July 27, 1880.

Application filed January 6, 1880.

To all whom it may concern:

Be it known that I, ABRAHAM N. WOLF, of Allentown, in the county of Lehigh and State of Pennsylvania, have invented a new and valuable improvement in Middlings-Separators; and I do hereby declare that the following is a full, clear, and exact description of the construction and operation of the same, reference being had to the annexed drawings, 10 making a part of this specification, and to the letters and figures of reference marked thereon.

Figure 1 of the drawings is a representation of a longitudinal vertical central section of my improved separator. Figs. 2 and 3 are transverse sections of the same. Fig. 4 is an end view thereof.

This invention has relation to middlings-separators; and it consists in the construction and novel arrangement of parts, as hereinafter shown and described.

In the accompanying drawings, the letter A designates the frame, which is usually of ordinary rectangular form, having removable sides and ends, held by buttons or other securing means.

A' represents the fan-case, and B the fan-shaft, having a pulley-connection, b. The fan-box is double, to accommodate a blower-fan, 30 B', and a suction-fan, C', the former discharging into a blast-box, D', at the lower portion of one end of the machine. Upon the fan-shaft, near the sides of the frame, are the eccentrics or cams a, which engage with the 35 ends of the upper arms, c, of the angle-levers D, said arms being provided with anti-friction rollers. These angle-levers D are pivoted to the frame, the location of the journals being between the shakers, as shown. By 40 means of upper extensions, c', they are connected with the upper shaker, and to the lower shaker by the lower arms, c''.

E designates the upper shaker, having a movable screen or cloth, e. The inclination 45 of this box is slightly downward from that end of the frame in which the fan is located, and is sufficient to allow the contents to be readily moved by the motion of the shaker-box toward its discharging end, that portion 50 upon the screen passing over and down through angular passages e' to the shaker below, and

that portion in the box of the shaker passing out through the discharge-spout f. Spring-arms D² serve as hangers for the shaker-box, and to give it a quick backward movement, 55 whereby the forward movement of the contents is accelerated.

E' represents the lower shaker, also hung from spring-arms D², and provided with a removable screen, e, as shown. This shaker is 60 inclined in the opposite direction from that of the upper shaker, to allow the contents to gravitate toward the blower end of the machine.

The shaker-boxes are made in cross-section, 65 somewhat angular in form, their sides being curved and shelving toward the lower central portion, which is flat, extending longitudinally from end to end. The bottom of the lower shaker is provided with an under discharge-trough, f', into which its contents are 70 passed through apertures g, governed by valves g'. The lower shaker receives that portion of the contents of the upper shaker which passes over its screen through the angular passages e'. 75

Upon the fan-shaft is formed a worm-thread, h, which engages with a gear-wheel, k, carrying an eccentrically-pivoted link, l, which is connected to the outer end of an arm, l', fastened to the journal of a horizontal blast-pipe, 80 m, which extends through the lower shaker under its screen, and is journaled at the other end, so as to have a vibratory motion as the gear-wheel k is turned by the worm h. Parallel with this blast-pipe and on each side of 85 it is a similar blast-pipe, m', also journaled at each end, the three journals of said pipes at one end of the machine carrying pulleys p, which engage with a belt, n, in the manner shown, thereby, when the central pipe is vibrated, giving a similar motion to the side pipes. These pipes extend into the blast-box 90 D', and have openings z' to receive the blast from the blast-chamber and discharge it through longitudinal slots or crevices r along 95 their upper surfaces, so that the blast is directed toward the under side of the lower screen, and has a lateral to-and-fro action thereon, keeping the cloth from clogging and blowing out the light fuzzy stuff, which is carried off by the action of the suction-fan.

L represents a shaft in the upper shaker,

having rocking bearings *s* and grip-leathers *t*, connected to said rocking bearings and to transverse slides *u*, moving on slotted ways *w* at each end of the shaker under the screen. 5 To these slides *u* are attached longitudinal cords *v*, which serve, when moved transversely by the means indicated, to clear the under surface of the upper screen. One of these slideways *w* is made movable, being attached 10 to a longitudinal slide, *w'*, having a handle, *H*, so that the cords may be slackened or tightened at will, or, by a quick pull, may be thrown upward against the under side of the screen-cloth. The rock-shaft *L* has upon its 15 journal end a pulley, *p'*, which is operated by the belt *n* to give said shaft a vibratory motion.

I am aware that shakers having opposite reciprocating movements and that oscillating 20 blast-pipes having spaced air-exits are not new, and I do not claim such devices, broadly.

Having described this invention, what I claim, and desire to secure by Letters Patent, is—

1. The combination, with the case *A*, having at one end a blast-chamber, *D'*, and a blower, *B'*, discharging into said chamber, of the oscillating pipes *m*, having longitudinal blast-slots under the lower screen, said pipes extending by one end into the blast-chamber, 30 and having inlets *z'* therein, and being provided at their other ends with pulleys *p*, the whipper-shaft *L*, its pulley *p'*, and the endless belt *n*, passing over the pulleys *p p'*, substantially as specified.

2. The combination, with the rock-shaft *L*, having the rocking bearings *s* and grip-leathers *t*, of the transverse slideways *w*, slides *u*, and clearing-cords *v*, substantially as specified.

In testimony that I claim the above I have 40 hereunto subscribed my name in the presence of two witnesses.

ABRAHAM N. WOLF.
